DESIGN FOR LACE

Richard Bloch, Pelham Manor, N. Y., assignor
to Liberty Lace and Netting Works, New York, N. Y., a corporation of New York

Application November 30, 1934, Serial No. 54,202

Term of patent 3½ years

To all whom it may concern:

Be it known that I, Richard Bloch, a citizen of the United States, residing at 24 Randall Place, Pelham Manor, in the county of Westchester, city and State of New York, have invented a new, original, and ornamental Design for Lace, of which the following is a specification, reference being

had to the accompanying drawing, forming part thereof.

The drawing shows a face view of a piece of lace
embodying my design.

I claim:

The ornamental design for lace, substantially
as shown.

RICHARD BLOCH.
